UNITED STATES PATENT OFFICE.

GEORGE FELIX EASON, OF MANNING, ARKANSAS.

MEASURING DEVICE.

1,295,015.

Specification of Letters Patent.

Patented Feb. 18, 1919.

Application filed September 13, 1916. Serial No. 119,927.

To all whom it may concern:

Be it known that I, GEORGE F. EASON, a citizen of the United States, residing at Manning, in the county of Dallas and State of Arkansas, have invented certain useful Improvements in Measuring Devices, of which the following is a specification, reference being had therein to the accompanying drawing.

10 The invention relates to measuring devices, and more particularly to the class of rope measuring devices.

The primary object of the invention is the provision of a device of this character, wherein ropes of different cross sectional areas can be accurately measured in any desired lengths as the same are let off of the supporting reels, thereby avoiding the use of an ordinary measuring hand rule.

20 Another object of this invention is the provision of a device of this character, which permits the hand pulling of the rope from its reel and the measuring of the same as to the required length, thus rendering the device useful in stores or the like, where rope is sold by linear measurement.

Another object of the invention is the provision of a device of this character which is simple in construction, strong, durable, efficient in operation, and inexpensive in manufacture.

With these objects in view, the invention consists in the features of construction, combination, and arrangement of elements, as 35 will be hereinafter fully described, illustrated in the accompanying drawings, and indicated in the claims annexed hereto.

In the accompanying drawings:

40 Figure 1 is a top plan view of a device constructed in accordance with the invention.

Fig. 2 is an end elevation thereof.

Fig. 3 is a vertical longitudinal sectional view through the device.

45 Fig. 4 is a fragmentary top plan view with the dial block removed showing in detail the gearing in the device.

Referring to the drawings in detail, the device comprises a bed or base 5 which is substantially rectangular in shape, although it may be of any other desirable shape and in this instance is made of hard wood, but can be made from any other suitable material. Formed transversely in the upper face of 55 the bed or base 5 is a channel or groove 6 which has intersecting it the spaced parallel

slots 7 which are longitudinally disposed on the base, and accommodate feed wheels or pulleys 8 fixed to a worm shaft 9, journaled in the groove or channel 6, the wheels or pulleys 8 being formed with peripheral grooves 10 for receiving ropes 11 and 12 which are of different cross sectional areas.

These ropes 11 and 12 are presumed to be wound upon suitably supported reels of any well known construction, the ropes being trained through guide eyes 13 mounted in the upper face of the bed or base 5 in alignment with the slots 7 for the guiding of the ropes onto the wheels or pulleys 8, the peripheries of the said wheels or pulleys each having teeth 14 on either side of its groove 10, so as to avoid the slipping of ropes of greater diameter than the ropes 11 and 12, when the device is used to measure relatively large rope and when the said rope is pulled from the reels in a manner presently described.

The bed or base 5 in its upper face from one end thereof to the slots 7, is formed with runways 15 which also assist in guiding the ropes 11 and 12 through the eyes 13 onto devices used to measure relatively large rope and when the rope is let off from the reels carrying the same.

At one side of the worm shaft 9 is a worm gear 16 which is formed with a stud 17 rotatively mounted in the bed or base 5 of the device, as shown, and this gear 16 meshes with a worm 18 formed on the worm shaft 9 so that on rotation of either of the wheels or pulleys 8, motion will be imparted to the worm gear 16 for operating an indicator hereinafter fully described.

Bridging the worm shaft 9 and gear 16 and positioned between the wheels or pulleys 8, is a dial block 19, the stud 17 of the gear 16 being extended upward through said block and being formed with a reduced upper end 20 on which is frictionally engaged the indicator comprising a pointer 21 which can be readily turned upon the stud 17 for the setting of said pointer, the pointer being held in position on the stud through the medium of a washer and a cupped spring washer 22 which are held on the reduced end 20 of the stud 17 preferably by having the eye in the spring washer effect a force-fit on the stud. Arranged concentrically to the reduced end 20 of the stud 17 and upon the upper face of the dial block 19 there is a scale 23 having designated numerals 24 over

which the pointer 21 is designed to move, so as to enable a person to accurately determine the desired length of a stretch of rope when fed through the device over one of the wheels or pulleys 8. The pulling upon the free end of the rope serves to rotate the shaft 9 which in turn rotates the worm gear 16 operating the pointer 21, causing the latter to travel over the scale 23 on the dial block 19 and enabling an observer to determine with accuracy the length of rope fed through the device for the measuring thereof.

The numerals 24 indicate in their numerical order the number of feet while the graduations between the numerals indicate fractions of a foot of a piece of rope. Fastened on the bed or base 5 are a pair of retaining members 25, each being in the form of a leaf spring with an upturned lip 26, so that the same can be manually gripped by the operator of the device.

Adjacent to these lips 26 on opposite sides of said members 25 are formed depending ears 27 which overlap opposite sides of the wheels or pulleys 8 to prevent the running off of the ropes 11 and 12 when engaged in the grooves in the wheels.

The feeding-out ends of the ropes 11 and 12 are extended through the slots 7 and also 30 through leads 28 formed in a cross bridge plate 29 secured to the under face of the bed or base 5 so that the ropes when trained over the wheels or pulleys 8 cannot work off the same upon the pulling of the ropes from 35 their supporting reels and the linear measuring of the ropes by the device.

In the operation of the device it will be assumed that the ropes 11 and 12 are trained over the wheels or pulleys 8 with the free 40 ends depending through the leads 28 in the cross bridge plate 29 and on the selection of either rope to be pulled upon for the feeding of the same from its supporting reel and the measuring of the length thereof, the 45 other rope is cast off of the wheel or pulley 8, which is effected by lifting the retaining member 25 upwardly and the said rope is taken from the wheel or pulley. Now by pulling upon the free end of the rope selected, the wheel or pulley 8 over which it

is trained will be caused to rotate and through the gearing, the indicator or pointer 21 is operated to travel over the dial block 19 to co-act with the digits and numerals 24 thereon so as to enable one to determine the 55 length of rope let off from the supporting reel.

It is obvious that either rope can be thrown off of its wheel or pulley when it is desired to feed out only a single rope thereby 60 rendering one rope ineffective in the device while the other is effective for measuring purposes.

It is thought that the construction and operation of the device will be clearly understood, and therefore, a more extended explanation has been omitted.

What is claimed is:

1. A device of the character described comprising a base, a pulley journaled upon 70 the base, the said pulley being grooved circumferentially and being provided with teeth on its periphery adjacent to either side of the groove, a dial block carried by the base and provided with indicating designations thereon, a pointer movable over the dial, a stud journaled in the base and carrying the pointer at its upper end, connections between the stud and the pulley, whereby rotary movement of the latter is imparted 75 to the former, and resilient means carried by the base for retaining a piece of rope in the groove of the pulley.

2. A device of the character described comprising a base, a pulley journaled upon 85 the base, said pulley being grooved circumferentially and being provided with teeth on its periphery adjacent to either side of the groove, an indicator mounted upon the base and operably connected with the pulley, and a leaf spring mounted upon the base and bearing upon the pulley at the periphery of the latter, the said spring having lips depending from its edges, so that the spring together with its lips may serve to secure 90 a piece of rope being measured in the groove of the pulley.

In testimony whereof I affix my signature.

GEORGE FELIX EASON.
